CLAIM

We claim the ornamental design for a test kit, as shown and described.

DESCRIPTION

FIG. 1 is an upper perspective view of a test kit in a first position;

FIG. 2 is a lower perspective view of the test kit in FIG. 1;
FIG. 3 is a forward plan view of the test kit shown in FIG. 1;

FIG. 4 is a rear plan view of the test kit shown in FIG. 1;
FIG. 5 is a left side view of the test kit shown in FIG. 1;
FIG. 6 is a right side view of the test kit shown in FIG. 1;
FIG. 7 is a top plan view of the test kit shown in FIG. 1;
FIG. 8 is a bottom plan view of the test kit shown in FIG. 1;

FIG. 9 is an exploded upper perspective view of the test kit shown in FIG. 1 in a second position;

FIG. 10 is an assembled upper perspective view of the test kit shown in FIG. 9;

FIG. 11 is a lower perspective view of the test kit in FIG. 10;
FIG. 12 is a forward plan view of the test kit shown in FIG. 10;

FIG. 13 is a rear plan view of the test kit shown in FIG. 10;
FIG. 14 is a left side view of the test kit shown in FIG. 10;
FIG. 15 is a right side view of the test kit shown in FIG. 10;
FIG. 16 is a top plan view of the test kit shown in FIG. 10;
and,

FIG. 17 is a bottom plan view of the test kit shown in FIG. 10.

The broken lines in the figures are environmental only and form no part of the claimed design.

1 Claim, 17 Drawing Sheets
